Primary Examiner — Ricky Pham(74) *Attorney, Agent, or Firm* — CARTER, DELUCA & FARRELL LLP(57) **CLAIM**

The ornamental design for a tray holder, as shown and described.

DESCRIPTION

FIG. 1 is a front perspective view of a tray holder in a closed configuration with the handle in a closed, locked configuration in its environment in accordance with the present design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an alternate front perspective view of the tray holder of FIG. 1 out of its environment with the handle in a closed, locked position thereof;

FIG. 9 is an alternate front perspective view of the tray holder of FIG. 1 out of its environment with the handle in an open, unlocked position thereof;

FIG. 10 is a front perspective view of the tray holder of FIG. 1 out of its environment in an open configuration with the handle in an open, unlocked position thereof; and,

FIG. 11 is a front perspective view of the tray holder of FIG. 1 out of its environment in a closed configuration with the handle in a stored, unlocked position thereof.

The broken lines shown in the drawings illustrate portions of the tray holder that form no part of the claimed design.

1 Claim, 9 Drawing Sheets(56)
